UNITED STATES PATENT OFFICE.

OSWALD DALE, OF NEW HAVEN, CONNECTICUT, ASSIGNOR TO THE ACME WIRE CO., OF NEW HAVEN, CONNECTICUT, A CORPORATION.

TRANSLUCENT SCREEN FOR PROJECTED PICTURE.

Application filed April 29, 1925. Serial No. 26,579.

Fig. 1 is a plan view of a screen embodying my invention.

Fig. 2 is a schematic face view with a section untreated.

5 Fig. 3 is a schematic transverse sectional view on the line 3—3 of Fig. 2.

My invention relates to an improvement in translucent screens for projected pictures, the object being to produce a screen fabricated with particular reference to securing 10 sharper images and to preserving color values than has been possible with the screens of the prior art. With these ends in view, my invention consists in a translucent 15 screen for projected pictures, the said screen being composed of silk warp and weft threads proportioned in width and spaced in weaving to present, in a given area of fabric, an area of silk greater than the aggregate 20 area of the interstices between the threads, and a vegetable-oil impregnating-compound.

In carrying out my invention, as herein shown, the fabric is composed of warp threads 5 and weft threads 6 crossing each 25 other at right angles, with minute interstices 7 between them; the width of the threads 5 and 6 in any given piece of silk considerably exceeding the size of the interstices between the threads, so that, in any 30 given area of screen, the aggregate area of all the threads is in excess of the aggregate area of all of the interstices, whereby the silk is the dominating factor in the surface of the fabric, rather than the spaces between 35 them, which has been the characteristic of translucent screens for projected pictures as heretofore made. Such a fabric is given a bluish tint by dyes, and then impregnated in a vegetable-oil compound 8, preferably 40 of a yellowish color, so that the ultimate screen fabric resulting from the blue-tinted silk and yellow oil is of a neutral greenish color, which I find to be exceedingly advantageous in the production of projected pictures, since it gives substantially unaltered 45 color values. I do not, however, limit myself to any color scheme.

My improved screen as thus constructed depends for its picture-reproducing qualities on the well-known light-diffusing qualities

ties of the extremely-tenuous, individual or ultimate strands of silk which go to make up each of the component threads of the fabric. In other words, I am taking advantage of the sheen, which is the salient characteristic 55 of silk as produced by the worm, for diffusing the light, which is something more than the diffusion of light from the surfaces of the fabric, but is, in fact, the diffusion of light by every ultimate strand of silk entering 60 into every thread of the fabric, whereas, in prior translucent screens, the function of the relatively wide-meshed fabrics employed has been to imprison and support the gelatin body of the screen, which has usually 65 been corrugated to secure some measure of diffusion of light.

Another remarkable feature of my discovery is that the pictures projected through the screen may be seen with extraordinary 70 definition at very acute angles with respect to the plane of the screen, whereas, in the prior art, beyond a certain angle, the picture became invisible. Still another remarkable feature of my discovery is that the picture projected upon the screen clearly appears upon the side thereof toward the projecting machine, as well as upon its forward side, which is toward the observer, enabling the operator to focus his pictures upon the 80 screen with the maximum of accuracy and convenience, without leaving his position at the machine, whereas, in using the screens of the prior art, he has been obliged to go around to the front side of the screen to observe the focus and to repeat these trips between the machine and the front of the screen until he at length hits upon the right focus. That old method entailed not only a 85 very considerable loss of time, but was arduous and failed of securing the precision of focus necessary to the best results. This quality of my improved screen of showing the picture with equal clearness on both sides I attribute to the power of diffusing light 90 inherent in every ultimate strand of silk, as explained above.

I claim:

As a new article of manufacture, a translucent screen for projected pictures, the said 100

screen comprising warp and weft silk threads proportioned in width and spaced in weaving so that the area of silk, in a given area of fabric, is in excess of the aggregate area of the interstices between the threads, the natural color of the silk being tinted with one color and then impregnated with a vege-

table compound of a complementary tint, so that the resulting screen is of a tint which will preserve color values.

10

In testimony whereof, I have signed this specification.

OSWALD DALE.
